Primary Examiner — Barbara Fox*Assistant Examiner* — Noah Perez(74) *Attorney, Agent, or Firm* — Zagorin Cave LLP; Robert W. Holland(57) **CLAIM**

We claim the ornamental design for a display stand with articulating arm, as shown and described.

DESCRIPTION

FIG. 1 is a front perspective view of a display stand with articulating arm comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; FIG. 8 is a bottom rear perspective view thereof; FIG. 9 is a front perspective view of the display stand with articulating arm shown in an environment of use; and, FIG. 10 is a front perspective exploded view of the display stand with articulating arm.

The broken line showing of the monitor, cables, and desk in FIG. 9 depicts environment and forms no part of the claimed

(Continued)

design. All other broken lines in the drawings depict portions of the display stand with articulating arm that form no part of the claimed design.

1 Claim, 9 Drawing Sheets
